UNITED STATES PATENT OFFICE.

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS.

OIL-BURNING FURNACE AND IGNITION MEANS THEREFOR.

Application filed March 12, 1926. Serial No. 94,142.

My invention relates to an ignition means and particularly to an ignition means adaptable for use with a gas or liquid fuel burner. One object is the provision of ready and 5 economical means for lighting such a burner, without the employment of a gas or electric ignition or a pilot light system. Another object is the provision of means for igniting the fuel in an enclosed burner without igniting the vapors or liquids which may exist 10 outside of the burner. Other objects will appear from time to time in the course of the specification and claims. I illustrate my invention more or less diagrammatically in 15 the accompanying drawings, wherein—

Figure 1 is a vertical section illustrating my ignition means as applied to a gas or oil burner;

Figure 2 is a sectional view, on an enlarged 20 scale, through the ignition member proper;

Figures 3 and 4 are similar sections illustrating various stages of the ignition process;

Figure 5 is a partial plan view;

Figure 6 is a section on the line 6—6 of 25 Figure 5;

Figure 7 is a vertical section through a variant form of my device;

Figure 8 is a section on an enlarged scale; 30 and

Figure 9 is an end view of the structure shown in Figure 8.

Like parts are indicated by like symbols throughout the specification and drawings.

Whereas my invention may be applied to 35 any suitable gas or liquid fuel burner I have illustrated it as applied to a burner wherein fuel oil is supplied to the bottom of the combustion chamber. A indicates the bowl or bottom of a fuel oil burner, A¹ is the upwardly continuing wall of such burner, A² is a surrounding housing spaced therefrom, and A³ any suitable supporting structure. A⁴ is a liquid fuel line communicating by 40 means of the elbow A⁵ with the bottom of the fuel receiving member A.

B is any suitable bearing or receiving member positioned in aligned apertures in the members A and A². Mounted in it is 45 an elongated tube B¹ the inner end of which is cut away as at B², the forwardly continuing portion B³ terminating in a downward curve or hook B⁴. The opposite end of the tube may be closed, for example by the screw threaded member C against which is com-

pressed a spiral spring C¹ the opposite end of which engages the plunger cylinder C². This plunger has an upwardly extending trigger stem C³ extending through a slot B⁵ in the top of the tube B¹. At its outer 60 end this slot is provided with a lateral extension B⁶ of such a size as to receive the stem C³.

The tube B¹ is provided, intermediate its ends, with the upwardly projecting member D perforated to receive a stem D¹ controlled by any suitable external handle, for example, the loop D², the projection D being closed by the screw threaded cap D³. At the bottom of the stem D¹ is any suitable scratching 70 device, for example the abrasively surfaced blade D⁴. E indicates any suitable match or ignitable member composed of or including an inflammable material adapted to be ignited by frictional contact with the 75 abrasive member D⁴.

Referring to Figures 7 to 9 K is a tube or passage penetrating through the outer cylinder A² and the inner burner cylinder A¹. It is provided at its outer end with a sleeve 80 K¹ formed to engage the ball member K². K³ is a flange downwardly depending from the upper side of the sleeve K¹ and is inwardly formed with an abrasive surface K⁴. Passing through the ball K² is the match receiving tube K⁵ the outer end of which passes through the actuating lever K⁶. K⁷ is any suitable hand hold member and K⁸ is a leaf spring secured to the lever K⁶ as at K⁹ and adapted to overlie the end of the tube K⁵. 90

My device is used in the following manner. The match E may be dropped through the slot B⁵, with the inflammable head E¹ facing to the left, as shown in the figures. The plunger C² is held in the withdrawn position in which it is shown in Figure 2, the stem C³ engaging the lateral notch B⁶. The slide D⁴ may be positioned across the interior of the tube as shown in Figure 6. A release of the stem C³ from the notch B⁶ 100 advances the match to the position shown in Figure 3, its further progress being limited by the abrasive member D⁴. The spring C¹ however is still compressed. The slide D⁴ is then upwardly withdrawn sufficiently to permit the passage of the notch. The abrasive contact ignites the match, and the plunger C², thrust forwardly by the compressed spring C¹, projects the match forwardly along the tube. The path of the 110

match is limited by the downwardly curved member B⁴ and the lighted match drops to the bottom of the member A.

If desired, I may initially set the slide D⁴ 5 to permit the passage of the match, with a partial abrasive contact. In such case the intermediate step of Figure 3 may be omitted, and the initial release of the plunger C² projects the match past the abrasive material, thus igniting it.

Referring to the form of Figures 7, 8 and 9, the match is positioned in the tube K⁵. The weight of the lever and the ball K⁷ holds the inner end of the tube in the position shown in Figure 8 and the inflammable match head engages the abrasive surface K⁴. When the match has been positioned as shown the leaf spring K⁸ is rotated or positioned to engage the end of the match, 20 thrusting the head of the match forcibly against the said abrasive surface. A sharp outward pull on the hand hold K⁹ or the lever K⁶ draws the match head rapidly downwardly across the abrasive surface and 25 ignites it. The continuation of the movement carries the match head downwardly below the lower edge of the flange K³ and the spring K⁸ then projects the ignited match into the interior of the burner.

Whereas I have described my invention, and shown it, as means for moving a match of the ordinary household type against or past a piece of abrasive material, it is obvious that I may broadly vary the details 30 without departing from the spirit of my invention. Thus I need not employ a match, and the inflammable material may be formed and mounted or supported in a variety of ways. Broadly stated, my invention consists 35 in projecting into a closed space an inflammable substance and in igniting the inflammable substance in the course of or as the result of its passage into the closed space, the ignition being preferably but not necessarily by frictional means.

I claim:

1. An ignition device for fuels adapted to be burned in a closed burner, which includes a guide passage apertured to receive an inflammable member, a holder for said inflammable member, positioned in said guide passage, propulsive means, for said inflammable member, associated with said holder and tending normally to project said member from said holder, and a friction member positioned in said passage and adapted initially to engage said inflammable member prior to its discharge into the burner, the guide passage being provided at its inner end with a discharge aperture into the burner.

2. An ignition device for fuels adapted to be burned in a closed burner, which includes a guide passage apertured to receive an inflammable member, a holder for said inflammable member, positioned in said guide passage, propulsive means, for said inflammable member, associated with said holder and tending normally to project said member from said holder, and a friction member positioned in said passage and adapted initially to engage said inflammable member prior to its discharge into the burner, the guide passage being provided at its inner end with a discharge aperture into the burner.

mable member, positioned in said guide passage, yielding propulsive means, for said inflammable member, associated with said holder, and tending normally to project said member from said holder, and a friction member positioned in said passage and adapted initially to engage said inflammable member prior to its discharge into the burner, the guide passage being provided at its inner end with a discharge aperture into the burner.

3. An ignition device for fuels adapted to be burned in a closed burner, which includes a guide passage apertured to receive an inflammable member, a holder for said inflammable member, positioned in said guide passage, propulsive means, for said inflammable member, associated with said holder, and a friction member positioned in said passage and adapted initially to engage said inflammable member prior to its discharge into the burner, the guide passage being provided at its inner end with a discharge aperture into the burner, and a deflecting member in the line of discharge of the guide passage.

4. The combination with a burner of an ignition device, comprising an inlet passage, means for aligning a frictionally inflammable ignition member therewith, yielding means tending normally to move it along said passage, an abrasive stop member adapted to engage said inflammable member, and means for imparting relative movement to the inflammable member and the abrasive stop member adapted at the same time to ignite and to release the inflammable member for projection through said passage.

5. The combination with a burner of an ignition device comprising an inlet passage, an abrasive stop member positioned in said passage, means for positioning a frictionally inflammable ignition member in said passage in engagement with said stop, means normally tending to thrust said member through said passage and means for laterally moving said inflammable member across said stop, adapted at the same time to ignite said member and to release it for projection through said passage.

6. The combination with a burner of an ignition device comprising an abrasive stop, means for positioning a frictionally inflammable ignition member in engagement with said stop, means tending normally to project said inflammable member in the direction of said stop and into said burner and means for imparting relative movement to the inflammable member and to the abrasive stop, adapted at the same time to ignite the inflammable member and to release it for projection into the burner.

7. The combination with a burner of an ignition device comprising an inlet passage, an abrasive stop member positioned in said passage, a holding member mounted adj-

cent the outer end of said passage and adapted to position a frictionally inflammable ignition member in said passage in engagement with said stop, yielding means on said holding member tending normally to project said inflammable member toward said burner and means for moving said holding member to move said ignition member across the face of said abrasive stop and to release it from alignment with said stop.

8. The combination with a burner of an ignition device comprising an inlet passage, an abrasive stop member positioned in said passage, a holding member pivoted adjacent said passage, including an open ended tube adapted to receive a frictionally inflammable ignition member, a handle therefor, a spring on said handle aligned with the outer end of said tube and adapted normally to thrust the frictionally inflammable ignition member therethrough, said open ended tube being adapted to be positioned normally in line with said abrasive

stop member and being adapted, in response to movement of said handle, to move the 25 inflammable member across the face of said abrasive stop and out of alignment therewith.

9. An ignition device for fuels adapted to be burned in a closed burner, which includes 30 a guide passage apertured to receive an inflammable member, a holder for said inflammable member mounted in said guide passage, propulsive means, for said inflammable member, associated with said holder, a friction member positioned in said passage and adapted initially to engage said inflammable member prior to its discharge into the burner, and means for moving said holder and for thereby moving said inflammable 40 member across the surface of and out of line with said friction member.

Signed at Chicago, county of Cook and State of Illinois, this 10th day of March 1926.

JAMES L. BREESE, JR.
